UNITED STATES PATENT OFFICE.

PHILIP YOE, OF DAYTON, OHIO, ASSIGNOR TO HIMSELF, E. W. HANLEY,
AND KERIEN FITZPATRICK, OF DAYTON, OHIO.

VOTING-MACHINE.

SPECIFICATION forming part of Letters Patent No. 752,276, dated February 16, 1904.

Application filed May 18, 1903. Serial No. 157,701. (No model.)

To all whom it may concern:

Be it known that I, PHILIP YOE, a citizen of the United States, residing at Dayton, in the county of Montgomery and State of Ohio, have 5 invented certain new and useful Improvements in Voting-Machines; and I do declare the following to be a full, clear, and exact description of the invention, such as will enable others skilled in the art to which it appertains to 10 make and use the same, reference being had to the accompanying drawings, and to the characters of reference marked thereon, which form a part of this specification.

This invention relates to improvements in 15 voting-machines. There are two classes of voting-machines, namely—that in which the voting is done by direct manipulation of keys, levers, or plungers and that in which the voting is done through setting mechanism which 20 is operated to effect a registration of the ballot as the voter leaves the inclosure or booth.

The present invention relates to the latter 25 class, and the means embodied therein appertain to mechanism for setting the selected candidate indicators by the voter and to mechanism which is operated by the voter upon leaving the inclosure or booth and causes the registration of the indicators selected.

The objects of the present invention are as 30 follows: first, to provide mechanism the manipulations of which require but little power and at the same time act in a positive manner and lock each actuating-frame in its set position; secondly, to provide simple and positive means for moving the registering-pawls 35 into and out of engagement with the counters; thirdly, to provide interlocking mechanism capable of making up a large multicandidate group—such, for example, as might be used 40 to record the electoral vote of a State—also means for concealing and rendering visible the operating-keys of the ballot-board, and other new and useful features peculiar to my invention will be disclosed throughout the detailed description thereof.

Preceding a detail description of my invention reference is made to the accompanying drawings, of which—

Figure 1 is a front elevation of the machine,

the supporting-legs being removed. Fig. 2 is a 50 rear elevation showing the straight-ticket operating-key connections and connections between the single-candidate setting-keys and the interlocking device. Fig. 3 is a side elevation of the machine, the inclosure-covering being removed. Fig. 4 is a partial sectional detail showing a single-candidate setting-key in its normal position and a single-candidate setting-key in its set position. Fig. 4^A, Sheet 5, is a view 55 similar to Fig. 4, showing the main actuating-frame at the lower limit of its initial stroke. Fig. 4^B is a top plan view of the actuating-frame and counters. Fig. 4^C is a detail of a portion of the main actuating-frame and the counter locking devices thereon. Fig. 5 is a detail of 60 the mechanism for throwing the counter-pawl in and out of contact with the counters if the voter wishes to change his selection before voting. Fig. 5^A is a detail of the mechanism shown in Fig. 5, the same being in a position 65 to engage the counters when the main actuating-frame is lowered. Fig. 5^B is a detail of the mechanism shown in Figs. 5 and 5^A, the same showing the actuating-frame in a position 70 after the counter actuating-pawl has been returned to its normal position after a registration, the main actuating-frame being on the limit of its downward movement. The actuating-frame is locked when in this position. Fig. 6 is a front elevation of a portion 75 of the machine, showing a portion of the ballot-board, parts being open to disclose the counters and other parts being broken away. Fig. 7 is a rear elevation of portions of the machine, showing a portion of the main actuating-frame, a counter actuating-pawl, and other mechanism. Fig. 8 is a detail of one 80 of the setting-keys and actuating-frame assembled. Fig. 9 is a modification of setting-key with actuating-frame assembled. Fig. 9^A is a view of the mechanism shown in Fig. 9, the same being in a set and locked position. Fig. 10 is a detail side elevation of the counter 85 concealing locking mechanism. Figs. 11 and 11^A are detail views of the actuating-frame; Fig. 12, details of the counter actuating-pawl; Fig. 13, details of antifriction-plates placed 90 between the counters and the actuating-frame.

Fig. 14 is a detail of the female member of the interlocking disks with adjacent frame shown in section. Fig. 14^a is a section on the line $\alpha\alpha$ of Fig. 14. Fig. 15 is a detail of one of the setting-keys; Fig. 16, details of the male member of the interlocking mechanism. Fig. 17 is a detail of the primary counter-wheel. Fig. 18 is a detail of a single-candidate interlocking device assembled. Fig. 18^a is a detail of the multicandidate interlocking device assembled; Fig. 19, a detail of the cam-shaft and cams, showing a portion of the connecting-rod of a straight-ticket key; Fig. 20, a detail of a portion of the main actuating-frame removed from the machine.

In a detail description of my invention similar reference characters indicate corresponding parts.

In the construction of the voting-machine now to be described in detail I have avoided the use of springs as far as possible, for the reason, as is well known to those skilled in the art, that these are undesirable elements in machines of this character. - I have further avoided the employment of screws and rivets in the movable parts of the mechanism, for the reason that it is well known screws become loose under the constant movement of the actuating parts and from long standing they often become rusted and are difficult of removal. Rivets are objectionable, owing to the fact that in dismantling the parts for repairs or for other purposes their detachment becomes difficult and renders the work more or less tedious. With my mechanism as constructed and assembled the parts may be detached almost instantly by the removal of a limited number of horizontal shafts or rods upon which the actuating mechanism is supported.

The main framework I may be of any suitable material and of any suitable design or shape to facilitate the mounting of the mechanism supported therein.

2 designates a ballot-board mounted in said frame and having a suitable number of openings 3, through which the ends of the straight-ticket operating-keys 4^a project in a position to be manipulated by the voter. Above these openings is inscribed the name of each ticket—for example, Republican, Democrat, Socialist, Prohibition, &c.

5 designates an inclosure-frame which is rigidly secured upon a suitable loose shaft 7, extending across the machine. This supports a suitable cover 8, of light material, which conceals the voter while he is selecting his candidates. The said cover 8 may be fastened to buttons 9 on said frame or in any other suitable way. One side of the inclosure-frame 5 is provided with a cam-slot 10, through which a stud 11 projects from the operating-lever 12. The said operating-lever is pivoted on a stud 13, and in the position shown in Fig. 3 the stud 11 in the slot 10 locks the inclosure-frame

in a lowered position. To elevate the inclosure-frame from this position, the lever 12 is lifted, and therewith the locking-stud 11 is raised out of the locking portion of the slot 10. The said stud then coming in contact with the straight portion of the cam-slot 10 acts to move said inclosure-frame up.

The operating-lever 12 has a suitable extension 14, which is actuated in either direction, according to the movement of the lever. This extension 14 has a cam-slot 15 with a locking portion. The end of a pawl-shaft 16 projects into this slot 15.

Referring further to the two cam-slots 10 and 15, Fig. 3, it may be stated that the locking terminals of these slots are in arcs of a circle having for its center the shaft 13, so that when the operating-lever 12 is moved to its lower position the said slots will be moved to positions which bring the stud 11 and the end 16 of the pawl-shaft in positions to lock the main actuating-frame 26 and the inclosure-frame 5. The main actuating-frame and the inclosure-frame are locked in this position so long as the operating-lever is in its lower position. The inclosure-frame cannot be elevated independently of the operating-lever, and the voter or occupant of the inclosure cannot depart therefrom without elevating said lever to unlock the inclosure-frame.

I will now describe the method for setting and voting a straight ticket. Referring to Figs. 1 and 3 of the drawings, it will be noted that the Republican straight-ticket operating-key 4^a is on the extreme left hand of the ballot-board. The mechanism operating in connection with that ticket is the lower horizontal row of candidates and consists of twelve duplicated sets. The mechanism for the next straight ticket—for example, the Democratic ticket—is the next lower horizontal row. The mechanism for the Socialistic straight ticket is the third horizontal row, and the mechanism for the Prohibition straight ticket is the uppermost row, all as is clearly shown in Fig. 1. The straight-ticket operating-keys 4^a are pivoted on a shaft 33, extending across the machine, said shaft being stationary and the operating-keys being movable thereon, so that each key may be moved independently. Each of said straight-ticket operating-keys 4^a is also pivoted to a connecting-rod 34 at 35. These connecting-rods are of different lengths, as shown in Fig. 2, and the lower ends thereof are connected to their respective horizontal cam-shafts 35', said cam-shafts being pivotally mounted in the main frame 1. Each cam-shaft 35' has a cam 36 rigidly connected thereto.

The longest one of the connecting-rods 34 is pivoted to the lower horizontal shaft 35', which is the shaft operating the Republican series of actuating mechanism by means of a boss or projection extending from one of the lifting-cams 36. The next longest connecting-rod 34 is pivoted in a similar manner to the

next upper shaft 35', and so on until the uppermost horizontal shaft 35' is reached, which is connected to the shortest connecting-rod 34 in a similar manner. It will be understood that there is a series of lifting-cams 36 projecting from each of the shafts 35', that cooperates with the individual-candidate setting-keys 4 of that series, said lifting-cams engaging with the rearward ends 20 of said setting-keys 4. As is clearly shown in Fig. 3, the rearward projecting portions 20 of said setting-keys 4 will be seen to occupy positions immediately above their respective lifting-cams 36. The operating-key 4^a, as shown in Fig. 3, actuates the cam-shaft 35' of the lower bank of mechanism, which is the straight Republican ticket. A depression of the operating-key 4^a by the voter within the inclosure will actuate all of the setting-keys 4 in that horizontal row or bank. After the operating-key 4^a is released it will return to its normal position by gravity. The voter then elevates the lever 12 to raise the inclosure and departs. Assuming that he desires to set the mechanism for a straight Republican ticket, he depresses the straight-ticket operating-key 4^a, which is shown in Fig. 1 beneath the word "Republican." This operation of depressing said key oscillates through connecting-rod 34 the lower cam-shaft 35'. The oscillation of this shaft moves upwardly its series of cams 36, and through said cams the setting-keys 4 are actuated from the rear ends 20. The actuating-frames 17 and their connecting mechanisms are moved into position, and upon further movement of the straight-ticket operating-key 4^a to its downward limit the setting-keys 4 lock the actuating-frames 17 firmly in the position to which they are moved. This completes the setting of a straight vote. The voter then seizes the operating-lever 12 and elevates it to its upper limit, and therewith the inclosure-frame 5, which permits his exit from the inclosure. This elevation of the operating-lever 12 lowers the main actuating-frame 26 through the slot 15 in the extension 14 and the pawl-shaft 16. The lowering of said frame 26 carries downwardly the pawl 23 and actuates the counters through the primary counter 25.

The ticket familiarly known as a "scratch ticket" may be voted in two ways. Assuming, for example, that a voter wishes to set the entire Republican ticket with the exception of one candidate on another ticket—for example, on the Democrat ticket—he depresses the straight-ticket operating-key 4^a of the Republican ticket. This, as before stated, sets the entire Republican ticket. He then places the mechanism for the candidate upon that ticket for whom he does not wish to vote out of an operative position or in its former normal position. He then depresses the individual setting-key 4 of that particular candidate upon the Democrat ticket and ele-

vates the operating-lever 12, as formerly described, and departs from the inclosure. In voting a scratch ticket another method may be employed, which is that of setting the individual-setting-keys 4 of the several series 70 for the candidates desired irrespective of the straight-ticket operating-keys.

Having shown the different methods of voting, I will now describe the single-candidate mechanism which is duplicated throughout 75 the machine.

Referring to Figs. 4 and 5^a, the setting mechanism for a single candidate is actuated through the depression of a setting-key 4, the finger end 4' of which is exposed at the front 80 of the machine. These keys are all of similar construction, and a detail of the same is shown in Fig. 15. The key 4 is pivoted at 19 on its respective actuating-frame 17, and it has a cam-slot 18, a portion of which is on an arc 85 of a circle having the pivot 19 for its center. A horizontal rod 21 projects through the slot 18 and extends the entire width of the machine, engaging in a similar manner every other setting-key of its series. Each of said 90 keys has a rearward projection 20, which is instrumental in the operation of the setting mechanism for a straight ticket, as hereinbefore described. The actuating-frame 17 is mounted loosely on a horizontal shaft 22, 95 which extends through the machine and supports the frames 17 of a series, as well as the counting-wheels of a series. 23 designates a pawl for operating the primary wheel 25^c of a counter shown in Fig. 4^b. This pawl is 100 shown in Fig. 12 and is pivoted on the shaft 16, which is supported on the main actuating-frame 26, which frame is operated through the cam-slot 15 and shaft 16, as hereinbefore stated. Referring to the pawl, as shown in 105 Fig. 12, the end 25 thereof is lowered by the depression of the setting-key into a position to engage with the ratchet-wheel 25^c of the primary counter when the setting is completed, the completion of the vote being 110 effected by elevating the lever 12 and lowering the main actuating-frame 26, as hereinbefore described.

In depressing the setting-key 4, as before stated, the pawl 23 is oscillated rearwardly 115 and the actuating-frame 17 is oscillated therewith, and the frame and necessarily the pawl 23 become locked in that position by reason of the setting-key being moved to a position which brings the slot 18 in a locking position 120 with the rod 21. The movement of the actuating-frame 26 imparted in the depression of the setting-key 4 causes a projection 17^c on said frame to come in contact with projection 24 on the pawl and as a consequence moves 125 said pawl in a position for the nose 25 to engage with the ratchet-wheel of the primary wheel of the counter when the main actuating-frame 26 is lowered. (See Figs. 4, 11, and 12.)

I have above described the operation of plac-

ing the mechanism in a condition to vote for a single candidate on any particular ticket. Should the voter desire to change his selection, the pawl 23 must be placed in its normal position, as shown in Figs. 4 and 5. The setting-key is removed from Fig. 5 in order to show the normal positions of the pawl and actuating-frame. The setting-key is elevated to its original position. This causes the frame 17 to assume such normal position, which carries the cam projection 17^c away from the pawl. The projection 17^d comes in contact with the nose 25^b of the pawl and throws said pawl to its normal or vertical position. Fig. 5^a shows said parts in a set position. The setting of the mechanism for the newly-selected candidate is in accordance with the manner hereinbefore described. The vote is registered as follows and through the following mechanism: The operating-lever 12 is elevated by the voter who is in the inclosure. This elevation unlocks the inclosure-frame and the main actuating-frame 26, as hereinbefore described. The inclosure-frame is elevated, while the main actuating-frame 26 is lowered. As the pawl is lowered by the said main actuating-frame 26 in the elevation of lever 12 the long arm of said pawl having the side projection 25^a rides beneath a projection 29 on the side 30 of the division-plates 28. (See Fig. 4.) The projection 29 locks the pawl in its operative movement positively. When the projection 25^b of the short arm of the pawl in its descent makes contact with the inclined surface 17^e of the actuating-frame 17, the pawl is oscillated in the direction of the lug or projection 29, which brings the long arm of said pawl on the other side of the projection, as shown in Fig. 5^b. As the device is shown in said figure the long arm of the pawl is behind the short arm and cannot be seen. The short arm is shown in this view in order to render more clearly the position of said arm relatively to the inclined surface 17^e of the actuating-frame. Upon the main actuating-frame 26 there is rigidly secured a counter-lock 27, which moves downwardly in unison with the pawl. The upper end 27^a of this lock engages the primary counter when the main actuating-frame 26 is at the limit of its down movement. Fig. 4^a shows the locking device 27 in a locking position with the counter. In the descent of the main actuating-frame 26 the pin 31^a thereon comes in contact with the rearward extension 20 of the setting-key and moves said key out of its locked position and unlocks the actuating-frame 17. In the downward movement of the main actuating-frame 26 projection 31 on cross-bar 30 engages with projection 17^e on the actuating-frame 17 and forces said actuating-frame downwardly to its normal position. The cross-bar 30, which is attached to the main actuating-frame 26, as before stated, continues to move downwardly, and the projection 31 thereon passes in the

rear of projection 17^e on the actuating-frame 17 and forms a lock to lock said actuating-frame 17, as shown in Fig. 5^b. The entire voting mechanism thus becomes locked in a position to prevent an operation of the same until the main actuating-frame 26 is again elevated. The vote is complete at this point. The next voter who enters the inclosure lowers the operating-lever 12. This elevates the main actuating-frame 26, and with it the pawl 75 and the counter-lock 27 in the upward limit of the movement of said frame 26. The lower projection 27^b of the counter-lock engages the teeth of the primary counter-wheel and holds the same until the next operation. (See Fig. 4.) 80 The main actuating-frame, consisting of the vertical members 26 and cross-bars 30, is properly guided above by an oscillating frame consisting of arms 53, which are fixed to an oscillating shaft 54, the latter shaft being suitably 85 journaled in the stationary part of the main frame. There are also suitable side guides in the frame for said main actuating-frame. The vertical members of the said main actuating-frame have a series of openings 55, in which 90 pawl-shafts 16 are mounted. (See Fig. 20.) The division-plates 28 are secured to upper and lower horizontal bars 28', which are secured between the uprights 1 of the main framework. 95
I will now describe the ballot-board as shown in Fig. 1, the concealing-shaft by which the counters are concealed during the voting period, and I will also describe the construction of the frame which holds the label bearing the 100 name of the candidate.
Referring to Figs. 11 and 11^a, 17^e designates the front portion of the actuating-frame 17, which supports the label upon which the candidate's name appears, the label being 105 placed within the slot 17^b. The candidate card or label is maintained securely within said slot 17^b by means of a locking-shaft 37, which extends the width of the machine and is supported in the division-plates 28 and sides of the main framework 1; but said counters may 110 be visible for inspection by the proper officers. The said concealing-shaft has a portion thereof cut away, as at 38, so that when said shaft is oscillated a sufficient extent the milled-out or cutaway portion thereof will be brought to a position that enables the counters to be seen. This shaft 37 is under sole control of the proper officer by means of a locking device 39. (Shown in Fig. 10.) Said locking device 39 is pivoted to the side of the main framework 1 in the rear of the portion 37', which extends from the end of the shaft 37. In Fig. 6 the concealing-shaft 37 is shown in an oscillated position, which permits of an exposure of the counters. The candidate card or label has been lowered to make the sight-opening 56 sufficiently large, the said candidate-card frame being lowered by depressing the setting-key 4. The counting-wheels, it 120 125 130

will be understood, are of well-known construction and operation. In Fig. 17 I have shown a detail of the primary counter-wheel, the same being provided with a spring 40, which frictionally controls the operative movements of the wheels. The counters are maintained in a position free from contact with the actuating-frame 17 by antifriction-plates 41', which are loose on the counter-shaft 22, and are prevented from rotating by the slotted projection 57, engaging with a stationary rod 58, extending horizontally through the machine, said rod likewise engaging the anti-friction-plates of the series. In Figs. 9 and 9^a I have shown modifications of the setting-key. These modifications consist in changing the position of the fulcrum of said key and also in changing the position of the cam-slot therein. For example, 19' designates a shaft extending through the machine and on which all of the setting-keys 4 of a particular series are loosely mounted. This shaft 19' constitutes a permanent pivot, while in the other construction the pivot 19 is movable. The cam-slot 18', which is substituted in this modification for the cam-slot 18, is an open slot and is provided in an extended portion of the key in a position to engage with a stud 21'. The stud 21' is on an actuating-frame 17. As shown in Fig. 9^a the key is in its set position. In this position the stud 21' is out of the slot 18' and the actuating-frame 17 is locked from the position shown in Fig. 9, the latter being its normal position. In Fig. 9 it will be seen that the stud 21' is moved out of the slot 18' and its radial portion 18" is locked against said stud 21'. In order to prevent the operation of more than one setting-key 4 at a time of its respective series—for example, the keys of a series of governors—I have provided interlocking devices consisting of male and female spreaders. In Fig. 18 of the drawings the interlocking mechanism, as shown, is adapted for voting a single candidate in a series, and this consists of a series of interlocking spreaders having a series of projections 44 and an extension with a slot 45, with which the lower end of the connecting-rod 46 is connected by means of a pin 46', which enters said slot, or any other suitable pivotal connection may be employed. 41 designates the female spreader, the same having a series of depressions 42, into and out of which the projections of the male spreader move. The female spreaders are prevented from rotating, but must have lateral movement. Therefore they each have a projection 51, which enters a longitudinal slot 52 in the horizontal portion 48 of a frame having abutments 49. The male spreaders 43 have both an oscillatory reciprocating movement and a lateral movement. In providing a frame 48 49 for a single-candidate interlocking mechanism it will be understood there is only sufficient space between the two abutments 49 to allow one

male spreader to disengage its companion spreader in performing its interlocking operation. (See Fig. 18.) The assemblage of interlocking spreaders, as shown in Fig. 18^a, is adapted for multicandidate or group voting—⁷⁰ for example, two candidates for the same office. Each group of spreaders is mounted in a similar manner upon shaft 50, secured to the side abutments 49 of the frame.

The spreaders, as shown in Fig. 18^a, have two operating-spaces or sufficient space between the abutments of the frame for two spreaders to operate, and it will be understood that where three or more candidates are to be voted for a single office the spaces between the abutments 49 will be further multiplied. In Fig. 2 three single-candidate interlocking devices and one multicandidate interlocking device adapted for two candidates for a single office are shown. The individual frames supporting these interlocking devices are detachable from the main framework of the machine. For example, it will be seen from Fig. 2 that by detaching the connecting-rods 46 from the spreaders of two single-candidate interlocking devices they, together with their frames, may be removed from the machine and a group of spreaders for a multicandidate interlocking device be substituted therefor. The frames in which the spreaders are mounted are themselves detachably mounted in the main framework of the machine by dovetail connections or otherwise. Figs. 18 and 18^a show the spreaders operated, and it will be understood that while in this position no other setting-key of their respective series can be operated.

In the setting movement of the key 4 the actuating-frame 17 is moved upon the counter-shaft 22 to the position shown in lower part 105 of Fig. 4, and the interlocking device of that particular setting-key is actuated through the connecting-rod 46 to separate the spreader, and thereby lock the remaining setting-keys and connected mechanism of that particular series. It will be observed that the movements of all the actuating parts throughout are in the same plane or in the same direction. In other words, there are no movements at angles to each other. This is an important item, for the reason that thereby I am enabled to avoid a certain amount of friction that would be unavoidable were the movements at angles to each other.

I do not wish to limit myself to the exact construction herein shown and described for locking the actuating-frame and connected mechanism by the setting-key itself.

Having described my invention, I claim—

1. In a voting-machine, the combination of an interlocking device, an actuating-frame adapted to operate the interlocking device, a setting-key connected with said actuating-frame, said key being movable into and out of a setting position, and means on said key for locking the actuating-frame.

2. In a voting-machine, the combination with a main actuating-frame, a series of pawls mounted thereon, a series of actuating-frames adapted to operate said pawls, and a series of setting-keys to set said actuating frames and pawls, and means coöperating with said keys whereby the actuating frames and pawls are locked in their set positions by the final movement of the setting-keys.
- 10 3. In a voting-machine, the combination of an actuating-frame, an interlocking device and connections actuated by said frame, setting-keys more than one of which is prevented from being operated at a time, by said interlocking device, each of said keys being capable of moving into and out of a setting position, and means on each of said keys for locking the actuating-frame and the interlocking device, in each set position.
- 15 4. In a voting-machine, the combination of an actuating-frame, an interlocking device and connections actuated by said frame, setting-keys more than one of which is prevented from being operated at a time by said interlocking device, each of said keys being capable of moving into and out of a setting position, means on each of said keys for locking the actuating-frame and interlocking device in each set position, and means on said keys for returning the actuated parts to their normal positions.
- 20 5. In a voting-machine, an actuating-frame, interlocking mechanism connected with said frame, and a setting-key adapted to actuate said frame to set the mechanism in the initial movement of the key, and means actuated in the final or subsequent movement of said key whereby the actuating-frame is locked directly by the key.
- 25 6. In a voting-machine, the combination with an oscillating actuating-frame, a candidate-label holder secured thereto, and a setting-key to actuate said actuating-frame and to positively lock the actuating-frame in its oscillated position.
- 30 7. In a voting-machine, the combination with an oscillating actuating-frame, a candidate-label holder thereon, a setting-key mov-
- able into and out of position and adapted to oscillate and positively lock said actuating-frame, said key also being capable of positively returning said actuating-frame and label-holder to their normal positions.
- 35 8. In a voting-machine, the combination with an actuating-frame, of a setting-key adapted to actuate said frame and to lock it after the limit of the movement of said key which actuates said frame.
- 40 9. In a voting-machine, a main actuating-frame, a series of pawls mounted thereon, a series of actuating-frames one of which operates with each pawl, a series of setting-keys, a series of counters operative by said pawls, means for actuating the main actuating-frame from the exterior of the machine, and means for restoring the pawls to their normal positions when the main actuating-frame is at the limit of its downward stroke.
- 45 10. In a voting-machine, a series of interlocking devices, a series of actuating-frames, a series of setting-keys, connections between said actuating-frames and said interlocking devices, a straight-ticket operating-key, a cam-shaft actuated thereby and adapted to set the setting-keys of an entire series simultaneously.
- 50 11. In a voting-machine, a series of counters in combination with an oscillating concealing-bar arranged in the front thereof, and means for locking said bar in a position to conceal the counters.
- 55 12. In a voting-machine, the combination with a main framework, division-plates secured thereto, counters and actuating-frames mounted between said division-plates, a shaft extending through said division-plates, and a series of anti-friction-plates mounted on said shaft to prevent the counter mechanism from binding.
- 60 13. In testimony whereof I affix my signature in presence of two witnesses.

PHILIP YOE.
